UNITED STATES PATENT OFFICE.

WILLIAM O. WARNEs, OF CHICAGO, ILLINOIS, ASSIGNOR OF ONE-HALF TO FRANK G. BUSH, OF CHICAGO, ILLINOIS.

ACCELERATOR ATTACHMENT FOR AUTOMOBILES.

1,184,903.

Specification of Letters Patent.

Patented May 30, 1916.

Application filed October 28, 1914. Serial No. 869,085.

To all whom it may concern:

Be it known that I, WILLIAM O. WARNEs, a citizen of the United States, residing at Chicago, in the county of Cook and State of Illinois, have invented certain new and useful Improvements in Accelerator Attachments for Automobiles, of which the following is a specification.

The present invention relates to an attachment adapted to be operated by the foot of the driver for controlling the position of the throttle valve and so governing the speed of the engine, such device being generally known as an accelerator.

The objects of the present invention are to provide an accelerator actuated by the foot of the driver which may be operated from the opposite side of the engine to that on which the carburetor is located.

A further object of the invention is to so arrange the connection between the foot accelerator and the throttle valve as to enable movement of said valve without actuating or disturbing any hand operated accelerator which may be in place upon the car, and to so arrange the connection from the foot accelerator to the valve as to permit of the free and unimpeded use of the hand accelerator if the same should be desired.

A further object of the invention is to provide an accelerator of the class described, which will be extremely cheap and simple of manufacture, will contain no involved or delicate parts, which could in any wise become impaired during ordinary use and destroy the efficiency of the device, and to so construct the parts forming the attachment as to enable them to be placed on the car without any alteration in the structure thereof, except the boring of one small hole in the toe board of the floor of the car, and after their placement allow of their ready removal, if the same should be necessary for any reason.

The invention further consists in the features of construction and combinations of parts hereinafter described and claimed.

In the drawings: Figure 1 is a plan view showing diagrammatically the parts together with portions of the operating mechanisms of an automobile, and also a portion of the car body, and further showing the accelerator attachment of the present invention in operative position; Fig. 2 is a side

elevation of the parts shown in Fig. 1 with the steering rod removed; Fig. 3 is a plan view of certain portions of the car mechanism with the parts comprising the attachment of the present invention in the positions assumed when the foot pedal is operated to open the throttle valve; Fig. 4 is a view similar to Fig. 3 showing the position assumed by the parts when the throttle valve is open by actuation of the hand accelerator; Fig. 5 is a section showing the connection between the rod of the hand operated accelerator mechanism and the connection to the throttle valve; and Fig. 6 is a detail showing one form of foot rest capable of use in conjunction with the present invention.

As stated, the present invention relates to an attachment adapted to be used upon an automobile for the purpose of controlling the opening and closing of the throttle valve of the engine and thus controlling the speed of the same. Owing to the fact that in most instances the speed of the engine will be almost constantly increased or decreased because of the varying conditions met during driving, it is extremely advantageous to arrange some form of mechanism for controlling the engine speed which is quickly and easily operated by the driver. As stated, the control of the engine speed is brought about by the opening and closing of the throttle valve and the most satisfactory way of controlling this valve, is by means of a pedal placed in the floor of the car and adjacent the clutch, brake and other pedals used for governing the driving of the car.

In certain types of cars it is extremely difficult to arrange a foot pedal for accelerating purposes. This is particularly true of that type of car known as the "Ford", because of the fact that in this type of car the steering wheel is located upon the left hand side of the engine, and the carburetor upon the right hand side so that any connection to the throttle valve must cross from the left side of the engine to the right. Owing to the fact that the driver sits on the left hand side of cars of this type, if any pedals, etc. for operating the throttle valve were placed on the right hand side, the presence of the passenger sitting beside him would interfere with the operation of the pedal with a consequent discommoding of both the driver and passenger. And so to have a practical foot accelerator for this

type of car, it must be placed on the left hand side of the car. For the above reason, the type of car above referred to, namely, the "Ford", is equipped with a hand 5 operated accelerator which is located just below the steering wheel, and in grading the speed of the engine the driver must necessarily be moving the finger piece of the hand accelerator back and forth necessitating the maintenance of both hands continuously upon the steering wheel while driving, and rendering useless for all practical purposes, one hand for steering purposes, this hand being employed in operating the 10 hand accelerator. This hand method is, therefore, not a satisfactory way of controlling acceleration, it being a great deal more convenient and satisfactory to control the speed of the engine by the foot of the driver, 15 leaving his hands entirely free for steering purposes.

In the present invention a device is set forth for producing acceleration by means of a foot pedal, which pedal is located on 20 the opposite side of the engine from that on which the carburetor is located and the device therefore is particularly and especially adapted for use with the "Ford" car, although, of course, the invention is in no 25 wise limited to this type of car, but could be applied to other types where similar conditions existed or to which it was found applicable.

Referring now to the drawings, and particularly to Fig. 1, the device is shown in connection with a motor 7 and adjacent the motor is located a carburetor 8. In the construction shown an arm 9 extends outward from said carburetor, and the movements of this arm actuates a butterfly or other valve in the manifold of the engine, such valve being termed a throttle valve. The foregoing arrangement of parts is characteristic of the "Ford" car, although the mechanism of this type of car is used only for illustrative purposes, and is not deemed to be a limitation on the present invention. In the type of automobile illustrated in the drawings the steering post 10 extends on the opposite side of the engine, from that side upon which is located the throttle valve and carburetor, and this steering post extends up through the dash of the car and has affixed at its outer end the usual steering wheel, not shown. The usual pedals 11 are located in the toe board of the floor of the car and below the steering wheel, and, therefore, the logical position for the foot accelerator in such a type of car is on that side of the car 55 upon which is located the steering wheel and operating pedals, and in case of the present invention the accelerator is placed in this position.

The attachment which connects to the arm 60 9 and controls the movements of the throttle

valve, forms the subject matter of the present invention, and consists of a link or rod 12 which extends crosswise of the engine and through the space 13 in the motor casing to the opposite side of the engine, said link is connected at one end 14 to the arm 9 and is formed with a loop or bend 15 intermediate its ends. Engaging with said loop or bend is one end of a rod or link 16, the other end of said link being connected to an arm 17 of the bell crank lever 18, which lever is supported by a bracket or support 19 and the lever moves or swings about a pin or other member 20 which joins it to this bracket. In the type of motor illustrated 70 the water pipe 21 is attached to the left hand side of the engine, and is connected up to the engine casing by means of bolts 22, the accelerator attachment of the present invention is so designed and arranged, that 75 the bracket 19 may be secured in place by simply removing one of the nuts of one of the bolts 22 which holds the water pipe in position, placing the bracket on said bolt, and replacing the nut, which action merely 80 amounts to placing a washer on the bolt. This bracket 19 is the main support for the accelerator attachment, and from the foregoing it will be readily seen that the device can be attached to the car structure without 85 any trouble or inconvenience or without 90 making any change in such structure utilizing a bolt which is of necessity present in all motors of this type.

The arm 23 of the bell crank lever 18 has 95 connected thereto one end of a rod or link 24. The other end of the rod engages with an arm 25, depending from a rock shaft 26 and in the construction shown the arm 25 is an integral part of said rock shaft. The 100 arm 25 extends through an opening 27 in the toe board of the floor of the car and the rock shaft 26 is mounted and held in position by suitable journals or brackets 28 attached to the floor of the car. The other end of the 105 rock shaft from that to which the arm 25 is attached has secured thereto or has formed therewith a foot piece in the shape of a pedal 29. This pedal, as will be observed from Fig. 1, lies adjacent to the ordinary control 110 pedals of the car; that is the brake, clutch and high and low speed pedals. In order to enable the foot to remain steady on the 115 pedal, a foot rest 30 is attached to the floor of the car and located adjacent to the pedal, and as shown in Fig. 1 at the side thereof. The type of car known as the "Ford" employs 120 a hand control for this throttle valve which hand control is operated by actuation of a finger piece usually located just 125 below the steering wheel, which finger piece is connected to a rod 31 which extends parallel to the steering rod and is rocked by actuation of the finger piece above described. This finger piece connection is so well known 130

in the art that illustration of the same is not deemed necessary in connection with the present invention. In the present invention an arm 32 is attached to the rod 31, and this 5 arm receives at its free end a crosswise extending stem 33, terminating in a head 34 through which passes, with a sliding fit, the link 12. A washer 35 is fixed to the end of the link 12, and lies as shown beyond the 10 stem 33, and the head 34 abuts against the washer 35 with the part as shown in Fig. 1. Extending from the head 33 to the loop 15 in the rod 12 and encircling said rod is a coil spring 36.

15 In the type of car where the steering wheel is upon one side of the engine and the carbureter and throttle valve upon the other, there must, of course, be a cross connection for the purpose of controlling the move-

20 ment of the throttle valve. In the construction of the present "Ford" car this connection is merely a rod connected at one end to an arm similar to the arm 32, which arm extends from a rod similar to the rod 31, and 25 connected at its other end to the throttle valve.

Therefore to apply the attachment of the present invention to a car of this type, all that need be done, is to take out the connection between the rod 31 and the carbureter, place the stem 33 in the hole in the arm 32 in which the previous connection was inserted, thereby placing in position one end of the link 12, then attach the other end of the link 12 to the carbureter, place in position the bracket 19, bore the small hole 35 through the toe board, place the rock shaft 26 and arm 25 in position and then place the links 16 and 24 in position. This method of attachment, as will be apparent, is ex-

40 tremely simple, can be performed by the car owner himself, does not need the service of a mechanic, does not require any change or disarrangement in the steering or other control mechanisms of the car, does not, in any 45 way, interfere with any other of the car mechanisms, and can be removed and positioned at will in a very short time and with no trouble or inconvenience. The operation is as follows:

50 When the position of the throttle is controlled by pressure of the foot of the driver, he places his foot upon the foot rest 30 and by a side wise rocking of the foot presses it down upon, or raises it from the pedal 29.

55 Such movements rock the shaft 26, pushing the arm 25 toward the front of the car. This pushes the link 24 forward, rocking the arm 17 of the bell crank 18, and forcing the arm 17 of the bell crank lever 18 in a circular path of 60 travel which carries it in a direction away from the engine. This pulls the link 16 in the direction of movement of the arm 17, and pulls the link 12 in a direction away 65 from the carbureter, actuating the arm 9 and opening the throttle valve. As the link 12

moves the loop or bend 15 therein, of course moves simultaneously. The link 12 during such movement slides through the opening in the head 34 of the stem 33, carrying the washer 35 away from said head and compressing the spring 36 between the head 34 and loop 15, all of which will be apparent from Fig. 3 of the drawing. The link 12 is thus placed under spring tension, and when the foot is released from the pedal 29, this 70 spring acts to force said link toward the carbureter, pushing back the arm 9 and closing the throttle valve. This link 16 is pulled by the action of the link 12 to rock the bell crank lever 18 and swing the arm 80 23 thereof toward the back of the car, pushing the link 24 back, forcing the arm 25 back and turning the rock shaft 26 to move the foot pedal 29 back to raised position.

It will be apparent that by movement of 85 the foot, the driver can control at will the opening and closing of the throttle valve and thus regulate and control the speed of the car by movement of the foot. Such control, by movement of the foot, as has 90 heretofore been stated, has been found in practice to be the proper and effective method of control. Owing to the slip connection between the link 12 and the head 34 of the stem 33, movement of the link 12 produced by operating the pedal 29, will not 95 move or affect in any way the hand control means for operating the throttle. But if it should be desired to use the hand control means, this can be accomplished by operating 100 the finger piece, thereby rocking the rod 31, which will swing the arm 33, carrying the stem 34 away from the engine casing as shown by dotted lines in Fig. 5 and by reason of the head 34 engaging with the washer 105 35 the rod 12 will be drawn back, as illustrated in Fig. 4, and the arm 9 actuated with the resultant opening of the throttle valve. If it is desired to close the valve by the hand operated means the rod 31 is 110 rocked by proper operations of the finger piece, the arm 31 is moved toward the engine casing, as shown by full lines in Fig. 5, and by reason of the spring interposed between the head 34 of this arm and the loop 115 15 in the rod 12, said rod will be moved forward and the valve closed.

I claim:

1. In combination with an automobile structure having a carbureter and throttle 120 valve on one side of the engine and a steering wheel upon the opposite side thereof, a link extending from the throttle valve in a direction crosswise of the engine and to the opposite side thereof, a bend in said link, a 125 foot piece operable from the steering wheel side of the car, a connection between said foot piece and the bend in the link, a hand operated member, a connection between the hand-operated member and that portion of 130

- the link lying beyond the bend, said connection embodying a member extending crosswise of the link through which the link passes with a sliding fit, and means on the 5 link lying beyond said member and adapted to be engaged and moved by said member, and compressible means extending between said member and the bent portion of the link, substantially as described.
16. 2. In combination with an automobile structure having a carburetor and throttle valve upon one side of the engine and a steering wheel upon the opposite side thereof, a link extending from the throttle valve 15 in a direction crosswise of the engine and to the opposite side thereof, a foot piece operable from the steering wheel side of the engine, a link and lever connection between the foot piece and the crosswise extending link, said connection joining said crosswise extending link at a point intermediate the ends of said link, a hand operated member, a connection between the hand operated member and the crosswise link joining said 25 link beyond the point of juncture of the foot piece connection with the link, said hand operated connection embodying a member extending crosswise of said link and through which the link passes with a sliding fit, an 30 abutment on the link beyond said member with which said member engages when the hand operated member is moved whereby a movement of the crosswise extending link is effected and resilient means interposed between said member and the point of juncture of the foot piece connection with said crosswise extending link, substantially as described.
3. In combination with an automobile 40 structure having a carburetor valve on one
- side of the engine and a steering-wheel on the opposite side thereof, a link extending from the throttle valve in a direction crosswise of the engine and to the opposite side thereof, a loop formed in said link medially 45 the length thereof and lying in a horizontal plane and extending toward the rear of the automobile structure, a bell-crank lever, means for supporting said lever, a link having a swivel connection at one end with 50 said bend and a pivotal connection at its other end to one arm of the bell-crank lever, and said pivotal connection being located in advance of the bend in said link, a foot-piece operable from the steering-wheel side 55 of the car, and a second link connecting said foot-piece and the other arm of the lever, whereby a pull is exerted on the cross link by the actuation of the foot-lever, moving said cross link longitudinally of itself with 60 a rectilinear movement, a hand operated member, a connection between the hand operated member and the crosswise link joining said link beyond the point of juncture of the foot-piece connection with the link, 65 said hand operated connection embodying a member extending crosswise of said link, and through which the link passes with a sliding fit, an abutment on the link beyond said member, with which said member engages when the hand operated member is moved, whereby a movement of the crosswise extending link is effected, and resilient means for moving said link in one direction, 70 substantially as described.
